TAP

Frank E. Rice, Detroit, Mich.

Application May 31, 1940, Serial No. 338,152

5 Claims. (Cl. 285—40)

The present invention relates to a tap construction and more particularly to a tap construction for carbonated beverages which provides a one-piece hollow body extending substantially the length of the tap thereby eliminating body joints and seals.

More specifically, the invention relates to a tap construction wherein a single one-piece hollow body member receives in rotatable relation therearound a one-piece adjustor or clamping ring.

In the usual tap construction, the body is formed of two parts held in connected relation by a rotatable coupling ring, which ring also serves to draw a tap bush into tight engagement with a connecting sleeve. These tap constructions are objectionable inasmuch as the joints between the body parts must be sealed to prevent gas leakage of the carbonated beverage flowing therethrough. Not only is the cost of production higher in manufacturing taps of this construction but special tools are usually required to replace the parts. In addition, the body joint provides a trap or pocket in which foreign matter or bacteria can accumulate.

The prior known adjustors for taps could only be made in one piece when the body member was made in two or more pieces. If a one-piece body member was used, a multi-piece adjustor had to be used.

The present invention now provides a tap with a one-piece body and a one-piece adjustor.

It is, therefore, an object of the present invention to provide a novel tap construction which is fluidproof.

Another object of this invention is the provision of a tap construction having a one-piece hollow body extending substantially the entire length of the tap.

A further object of the present invention is the provision of a tap construction in which all body joints are eliminated.

Another and further object of this invention is to provide a tap including a one-piece hollow body carrying a one-piece coupling ring.

Another and still further object of the present invention is the provision of a tap construction having a one-piece hollow body and a separable sleeve with novel self-adjusting washer means therebetween.

The novel features believed to be characteristic of the present invention are set forth with particularity in the appended claims. The invention itself, however, both as to its organization and manner of construction together with

further objects and advantages thereof, may best be understood by reference to the following description taken in connection with the accompanying drawing, in which:

5 Figure 1 is an elevational view illustrating a tap device constructed in accordance with the principles of this invention and loosely connected to a tap bush and barrel;

10 Figure 2 is an enlarged vertical cross-sectional view, with parts in elevation, of the tap construction illustrated in Figure 1;

15 Figure 3 is a view similar to Figure 1 illustrating separable parts of the tap disassembled from the body;

20 Figure 4 is a transverse cross-sectional view with a part in elevation, taken substantially along the plane indicated by the line IV—IV of Figure 2 and looking upwardly in the direction of the arrows;

25 Figure 5 is a transverse cross-sectional view, with a part in elevation, taken substantially along the plane indicated by the line V—V of Figure 2 and looking upwardly in the direction of the arrows;

30 Figure 6 is a view similar to Figure 5 illustrating a modified form of washer;

Figure 7 is a broken longitudinal side view illustrating the coil spring in its normal position before being shaped circular as shown in Figures 2 and 4;

35 Figure 8 is a view similar to Figure 4 illustrating a flat resilient washer substituted for the coil spring; and,

Figure 9 is a transverse cross-sectional view, 40 with a part in elevation, of the resilient washer illustrated in Figure 8 as seen when taken substantially along the plane indicated by the line IX—IX of Figure 8.

The tap 10 illustrated in Figure 1 is constructed for application to a standard bung or bushing *b* which is seated in the head of a barrel *B* and generally comprises an elongated one-piece body 11 of cylindrical hollow shape, a one-piece coupling sleeve 12, and a one-piece coupling ring or adjustor 13.

As best shown in Figure 2, the body 11 is hollow to receive a draught tube 14 therethrough. The upper end of the body has an integral enlarged portion 15 having an inner inclined face 16 for tightly seating a resilient washer 17 around the inserted draught tube 14 when pressure is applied downwardly on the washer. The resilient washer 17 is formed preferably of soft rubber or other similar material to effect a fluidtight joint between the body and the inserted draught tube.

The enlargement 15 is threaded on its exterior to receive an interiorly threaded cap nut 18 having handles 18a. A presser bushing 19 is rotatably mounted within the cap nut 18. As the nut is rotated by the handles 18a in its threaded engagement with the enlarged end of the body the bushing moves axially, without rotation, against the resilient washer to squeeze the latter into holding engagement with the tube 14. By moving the bushing axially without rotation, abrasion of the washer 17 is prevented.

The bottom end of the body 11 is provided with a flange 20, a square shoulder 21 and a reduced cylindrical end 22. A sealing washer 23 embraces the cylindrical end 22 and abuts the shoulder 21 of the lower end of the body, as shown in Figure 2. The sealing washer is arranged to engage the upper surface of the flange of the tap bush b when the tapping device 10 is applied to the bush.

Located substantially centrally of the body 11 is an enlarged portion 24 having formed thereon a pair of spaced annular recesses 25 and 26.

In the upper and shallower annular recess 25, there is seated a coil spring 27. As best shown in Figure 7, the coil spring 27 is provided at one end with reduced coils 28, the latter being either integrally connected to the larger coiled portion of the spring or being in the form of a separate shorter coiled spring threaded into the end of the main spring. The coils 28 are formed to threadingly engage within the larger coils at the opposite end of the spring 27 to form a circular spring, as illustrated in Figure 4.

A two-piece beveled washer 29 is seated within the lower and deeper annular recess 26. As shown in Figure 5, the beveled washer 29 is diametrically split to form half portions 29a and 29b. An outer corner of the split washer is beveled as at 30 for a purpose to be more fully explained hereinafter.

The coupling or connecting sleeve 12 surrounds the lower end of the body 11, as shown in Figure 2, and is provided at its inner end with diametrically opposed lugs 31 (only one of which is shown). These lugs are arranged to engage the under surfaces of the flange of the tap bush b to draw the upper surface of the bush flange against the resilient washer 23 for tightly securing the body of the tapping device 10 to the bush. When the tap and bush are so connected, the annular flange 32 of the coupling sleeve 12 engages the surface of the head of the barrel B thus stabilizing the tap and its inserted draught tube against tilting movement.

The coupling sleeve 12 extends upwardly and terminates adjacent the lower annular recess 26 in an exteriorly threaded portion 33. The threaded end 33 is beveled as at 34 for engagement with the beveled edge 30 of the removable washer 29.

As shown in Figures 2 and 3, the body 11 is provided with outwardly extending lugs 35 between the flange 26 and the enlarged central portion 24. These lugs have their major axes parallel to the longitudinal axis of the body 11 and are arranged to engage in vertically extending slots such as 36 provided on the inside of the coupling sleeve 12 (Fig. 2). This engagement prevents relative rotative movement between the coupling sleeve and the tap body when the coupling sleeve surrounds the body as shown in Figures 1 and 2.

The one-piece coupling ring or adjustor 13 is interiorly threaded for engagement with the

threaded end 33 of the coupling sleeve 12. An inwardly extending flange 37 formed integrally on the coupling ring 13 rotatably surrounds the enlarged portion 24 of the tap body and is retained for a limited endwise movement axially of the body by means of the coil spring 27 and the beveled washer 29. Wings or handles 38 are formed as a part of the ring 13 and are inclined to the axis of the body in a direction divergent from the coupling sleeve 12. It is to be noted that the coupling ring 13 and its integrally formed wings 38 may be removed from the body 11 when the beveled washer 29 is removed from its annular recess 26.

An interiorly threaded hollow boss 39 is formed as an integral part of the body 11 and extends divergently therefrom adjacent the upper enlarged portion 15. This boss or passaged neck is arranged to threadingly receive a hose nipple 40 to which is connected a fluid pressure hose (not shown).

A valve 41, of resilient material such as rubber having a passage therethrough for allowing fluid flow into the tap body only, is connected at the inner end of the hose nipple 40 (Figure 2).

Figure 3 illustrates the tapping device of Figure 1 when partially disassembled. To disassemble the tapping device 10, the handles 38 are rotated in a counterclockwise direction. The diametrically arranged ribs or lugs 35 cooperate with the grooves or slots 36 formed in the interior of the sleeve 12 to permit relative axial movement between the sleeve and the tap body while preventing relative rotative movement between them.

When the sleeve 12 has been released from threaded engagement with the coupling ring 13 and removed from the body 11 as shown, the coupling ring is maintained in operative connected relation to the body by and between the coil spring 27 and the beveled washer 29. The coil spring 27 is removed from the annular recess 25 by the insertion of an instrument such as a knife or screwdriver to stretch and move it upwardly against the passaged neck 39. The coupling ring 13 is then moved upwardly to allow the free removal of the beveled washer 29 from the annular recess 26.

Both the coupling ring and the coil spring may then be removed from the body 11 over its flanged end 20.

The upper cap nut 18 and the hose nipple 40 are removed by rotation in a counterclockwise direction for disengaging them from threaded relation with the body 11.

In applying the tapping device of the present invention to a barrel, the draught tube 14 is removed from the tapping device. The coupling ring 13 is loosened so that the coupling sleeve 12 is free to engage over the flange of the tap bush b whereupon the tapping device is rotated until the lugs 31 on the sleeve 12 contact the usual stops present in such a tap bush. Thereupon, the wings or handles 38 of the coupling ring are rotated which causes relative axial movement between the body 11 and the sleeve 12 to tighten the tapping device against the bush in operative relationship.

The draught tube 14 is then inserted with the cap nut 18 in loose threaded relation with the upper end of the body. The draught tube is moved downwardly until the lower end thereof engages the bottom of the barrel B whereupon the nut 18 is tightened to force the washer 17 into gripping engagement with the tube in which position the tapping device is ready for use.

In the event that pressure is required within the barrel to discharge its contents, air or gas pressure is admitted through the hose nipple 40 and the valve 41. The air or gas is restricted from passing upwardly around the draught tube by the gripping engagement therewith of the resilient washer 17. The draught tube 14 is fitted loosely in the lower portion of the body to allow fluid flow thereby into the barrel.

As shown in Figure 6, a U-shaped washer 42 may be substituted for the two-piece split washer 29. As shown, the edges 43 and 44 forming the U-shape are spaced slightly wider than the bottom of the annular recess 26. This allows the washer 42 to be inserted or removed from its annular recess when the coupling ring is positioned against the apertured neck 39. A beveled edge 45 is provided on the U-shaped washer 42 in the same manner and for the same purpose as the beveled edge 30 on the washer 29.

In Figures 8 and 9 there is illustrated a flat resilient washer 46, comprising a flat ring 47 of rubber or other similar material and a pair of semi-circular U-shaped metal washer supports 48 and 49. The sidewalls of the U-shaped supports straddle and embrace the flat surfaces of the ring with their connecting webs facing inwardly. The ends of the supports are positioned in spaced relation to allow the resilient portions of the ring therebetween to flex. The sidewalls of the U-shaped supports serve to limit the resiliency of the ring 47 and to provide more durable surfaces for contacting the shoulders of the annular recess 25 than if the ring 47 only was inserted therein.

A portion of the enlargement 24 on the body 11, adjacent the annular recess 25, is removed as at 50 to provide an opening into which a tool can be inserted for flexing and expanding the washer 46 to effect its removal from the annular recess 25. The provision of the washer 46 is for exactly the same purpose as the coil spring 27 and its removal from the body 11 is accomplished in the same manner as the removal of the coil spring.

From the foregoing description, it will be observed that this invention contemplates the construction of a tap having an elongated one-piece body which cooperates with a one-piece coupling ring and coupling sleeve to permit ready application and removal of a tap body to or from a flanged bush in a barrel. The one-piece coupling ring is retained in free rotatable relation on the one-piece body by the spaced removable means 27, 46 and 29, 42. These means provide a slot therebetween for receiving the flange 31 of the coupling ring therein. When the means, such as 29 or 42, are removed the coupling ring can be removed from the body.

The tapping device presents a further advantage by providing for the retention of the coupling ring on the body in a loose operative position when the coupling sleeve is removed. This enables the tap to be applied to a flanged bush easily and quickly without exerting pressure against the draught tube.

While particular embodiments of this invention have been illustrated, it will, of course, be understood that the invention should not be limited thereto since many modifications may be made and, therefore, it is contemplated by the appended claims to cover all such modifications as fall within the true spirit and scope of the present invention.

I claim as my invention:

1. A tapping device for use with a barrel having a bush, said device comprising a sleeve having means at one end for secured connection with the bush, an elongated body slidably engaging said sleeve and having means at one end for sealing engagement with the bush, a coupling ring slidably on said body and turnable in engagement with said sleeve to clamp said body to the bush, said ring being arranged slidable along said body for removal therefrom, and means for securing said ring in assembled relation to said body, said means comprising removable stop means on said body and interposed between said ring and the other end of said sleeve and arranged to abut the other end of said sleeve when said device is in clamping relation on the bush.
2. A tapping device for use with a barrel having a bush, said device comprising a sleeve having means at one end for secured connection with the bush, an elongated body slidably engaging said sleeve and having means at one end for engagement with the bush, a coupling ring slidable on said body and turnable in engagement with said sleeve to clamp said body to the bush, said ring being slidable along said body for removal therefrom, means for securing said ring in assembled relation to said body, said means comprising a first removable stop means on said body and interposed between said ring and the other end of said sleeve to abut the other end of said sleeve when the device is in clamping relation to the bush, and a second removable stop means on said body and disposed between said ring and the other end of said body.
3. A tapping device for use with a barrel having a bush, said device comprising a sleeve having means at one end for secured connection with the bush, an elongated body slidably engaging said sleeve and having means at one end for engagement with the bush, a coupling ring slidable on said body and turnable in engagement with said sleeve to clamp said body to the bush, said ring being slidable along said body for removal therefrom, means for securing said ring in assembled relation to said body, said means comprising a first removable stop means on said body and interposed between said ring and the other end of said sleeve, and a second removable stop means on said body and disposed between said ring and the other end of said body and comprising a member of resilient material yieldingly engaging said ring.
4. A tapping device for use with a barrel having a bush, said device comprising a sleeve having means at one end for secured connection with the bush, an elongated body slidably engaging said sleeve and having means at one end for engagement with the bush, a coupling ring slidable on said body and turnable in engagement with said sleeve to clamp said body to the bush, said ring being slidable along said body for removal therefrom, means for securing said ring in assembled relation to said body, said means comprising a first removable stop means on said body and interposed between said ring and the other end of said sleeve, means on said body and disposed between said ring and the other end of said body arranged defining a pair of longitudinally spaced shoulders, and a second removable stop means on said body and entered between said shoulders, said second stop means comprising a ring of resilient material and a pair of metallic members held in assembled relation by said ring and disposed guarding said ring against wear.

5. A tapping device for use with a barrel having a bush, said device comprising a sleeve having means at one end for secured connection with the bush, an elongated body slidably engaging said sleeve and having means at one end for engagement with the bush, a coupling ring slidable on said body and turnable in engagement with said sleeve to clamp said body to the bush, said ring being slidable along said body for removal therefrom, means on said body defining a first groove thereon, means on said body defining a second groove thereon longitudinally spaced from said first groove, said ring being provided with means

defining an inwardly directed flange normally positioned between said first and said second grooves, means for securing said ring to said body, said means comprising a removable stop member entered in said first groove and disposed between said flange and the other end of said sleeve to provide a seat for one face of said flange and an abutment for the other end of said sleeve, and a second removable stop member entered in said second groove and normally in yielding engagement with an opposite face of said flange.

FRANK E. RICE.
